UNITED STATES PATENT OFFICE.

THOMAS P. TYRRELL, OF AKRON, OHIO.

TOY BALLOON.

Application filed May 16, 1922. Serial No. 561,476.

To all whom it may concern:

Be it known that I, THOMAS P. TYRRELL, a citizen of the United States, residing at Akron, in the county of Summit and State of Ohio, have invented new and useful Improvements in Toy Balloons, of which the following is a specification.

This invention relates to certain new and useful improvements in toy balloons and has particular relation to a toy balloon which is provided with propelling means whereby the same may be caused to travel through the air.

The main object of the invention is to provide a propelling device of simple, inexpensive construction, which may be conveniently attached to an ordinary toy balloon to provide an attractive aerial toy.

A further object is to provide a device of light weight which may be attached to a toy balloon and which includes an air motor and a propeller with driving connections therebetween, whereby the motor may be operated by the escape of air from the balloon and the propeller rapidly rotated to drive the balloon through the air.

The above and additional objects are accomplished by the novel construction, combination and arrangement of parts hereinabove described and illustrated in the accompanying drawing, wherein I have shown a preferred embodiment of the invention, it being understood that the invention is capable of various adaptations and that changes and modifications may be made or substitutions resorted to which come within the scope of the claims hereunto appended.

In the drawings in which similar characters of reference have been employed to indicate like parts as the same may appear in the several views:—

Figure 1 is a side elevation of a toy constructed in accordance with this invention.

Figure 2 is a central vertical, sectional view of same.

Figure 3 is a side elevational view of the propeller and also showing the propeller shaft with the turbine blades secured thereto.

Figure 4 is an end view of same.

Proceeding now to a detailed description of the invention, the numeral 5 denotes a toy balloon preferably composed of rubber or similar thin, elastic material. The mouth of the balloon is provided with an annular bead 6 for a purpose to be hereinafter de-

scribed. The numeral 7 denotes a cylindrical member which is open at the bottom end and which is provided with an upper wall 8. The numeral 10 denotes a groove formed in the member 7 so as to extend therearound in spaced parallel relation to the lower edge thereof. The numeral 9 denotes a hollow stem which is secured in the wall 8 so as to extend coaxially therethrough and project from the upper and lower face thereof. The stem 9 projects downwardly from the wall 8 to a point below the lower edge of the member 7 and terminates in a hollow conical mouth piece 9^a. The numeral 11 denotes a hollow shaft which is rotatably mounted on 70 said stem and is secured thereon by means of the flange or washer 12. The hollow shaft 11 is provided at its upper end with a plurality of blades 13 which are preferably arranged so that each blade projects therefrom 75 at an angle to the radius thereof and terminates in spaced relation to the inner face of the cylindrical member 7. The lower end of the shaft 11 is provided with a propeller blade 14 which may be formed integral 80 therewith or attached thereto in any desired manner. An opening 15 is formed in the cylindrical wall of the member 7 at a point upwardly from the groove 10. The upper end of the stem 9 is provided with a flap 85 valve 16 which is arranged to permit the air to be forced inwardly therethrough and to prevent the air from escaping through said stem.

In operation, the mouth of a rubber balloon is stretched over the cylindrical member 7 and the bead 6 is seated in the groove 10, the said bead being of sufficient strength to retain the balloon 5 on the cylindrical member 7. The operator's finger is then firmly placed on the wall of the balloon at a point directly in front of the opening 15 and the wall is thus held against the side of the cylindrical member 7 so as to close said opening 15 and prevent air from escaping therethrough. The mouthpiece 9^a is then placed in the mouth and air is forced through the stem 9 until the balloon has been expanded to the desired size. The operator's finger is then removed and the toy is released, permitting the air thus confined within the balloon to escape through the opening 15. The elasticity of the balloon will cause the air to be forced through the opening 15, whereupon it will engage the blades 13 and 110

cause a rapid rotation of the shaft 11, thus rotating the propeller and forcing the balloon rapidly through the air.

Having thus illustrated my invention and 5 described the same in detail, what I claim as new and desire to secure by Letters-Patent is:—

1. In combination, a toy balloon, a closure member secured in the mouth thereof, 10 a valve controlled inflation stem extending through said closure member, a hollow shaft rotatably mounted on said stem, an air turbine associated with the upper end of said shaft, a propeller secured to the lower end 15 thereof and an opening arranged in said closure member to permit air to escape there-through and operate said turbine.

2. In combination, a balloon a closure

member secured in the mouth thereof means to inflate said balloon, an opening in said 20 closure member, an air turbine mounted on said member so as to be driven by air escaping from said balloon though said opening, a propeller and driving connection between said turbine and said propeller.

25 3. In combination, an elastic balloon, a closure member therefor, said closure member having an outlet opening and a valve controlled inflation opening, an air turbine associated with said member and arranged 30 to be driven by air escaping through said outlet opening, a propeller and driving connection between said turbine and propeller.

In testimony whereof I have hereunto set my hand.

THOMAS P. TYRRELL.
